UNITED STATES PATENT OFFICE.

LORENZ MUTHER, OF CHICAGO, ILLINOIS, ASSIGNOR TO THE UNION SPECIAL SEWING MACHINE COMPANY, OF SAME PLACE.

SEWING-MACHINE.

SPECIFICATION forming part of Letters Patent No. 445,122, dated January 20, 1891.

Application filed January 2, 1889. Serial No. 295,260. (No model.)

To all whom it may concern:

Be it known that I, LORENZ MUTHER, of Chicago, county of Cook, State of Illinois, have invented an Improvement in Sewing-Machines, of which the following description, in connection with the accompanying drawings, is a specification, like letters and figures on the drawings representing like parts.

This invention has for its object to improve that class of sewing-machines represented in United States Patent No. 344,493, dated June 29, 1886.

In this my present invention I have provided the throat-plate with a needle-deflector located a short distance below the throat-plate, the said deflector having tapering surfaces against which the points of the two needles employed will strike if deflected out of their proper path by any hardness or inequality of the material, the surfaces of the said deflector directing the said needles into a slot thereof side by side, so that both loops of thread thrown out from the eyes of the needles may be entered by the thread-carrying looper. The needle-deflector is so constructed that the parts thereof containing the inclined surfaces may separate one from the other. The looper near its heel is provided at its inner grooved side with a notch to leave a shoulder which catches and holds the loop of needle-thread as the looper moves backward, thus drawing the loops of needle-thread out of the way of the needles as they again descend through the material to enter the loop of thread carried by the looper. To prevent the loops of needle-thread held upon the looper as the latter is retracted or drawn out of the said loops of needle-thread from being drawn forward by the strain of the thread, so as to get in the way of the descending needles which are about entering the loop of the looper-thread, I have provided the throat-plate at its under side and at the right-hand side of the needle-hole with a transverse depression or groove and a finger against which the loops of needle-thread arrive and bear as the points of the needles descend between the looper and looper-thread, the outer or free end of said finger substantially holding the said loops until the point of the looper in its backward movement comes

to the finger, the outer end of the finger projecting over said depression.

The particular features in which my invention consists will be hereinafter pointed out in the specification and included in the claims at the end of the specification.

Figure 1 is a partial side elevation of a sewing-machine embodying my improvements, the cloth-plate being in section, the upper part 60 of the frame of the machine and the needle-bar-actuating lever and needle-bar being omitted. Fig. 2 is an under side view of the throat-plate with my improved needle-deflector and finger attached thereto. Fig. 3 65 shows a needle-deflector in perspective, right side up; and Fig. 4 shows the looper in different views.

The frame-work of the machine, the main shaft C', the needle-bar-actuating lever B, but 70 partly shown, the rocker-frame A², having the pivot m, upon which vibrates the arm 5, which receives the shank of the looper, the stud 6, forming part of the said arm and having fitted over it one end of the connecting-rod A', 75 which at its other end fitted over a pin at the lower end of the lever B, the forked arm A³, connected with one of the journals of the rocking-frame A², the said forked arm embracing an eccentric on the shaft C', the throat- 80 plate T, and the needle-bar c and its two needles a b are and may be all as in United States Patent No. 344,493 referred to, wherein like letters are employed to designate like parts. 85

In accordance with my invention I have provided the throat-plate at its under side with a needle-deflector d, consisting of a yoke-like piece of material extended from a block d', attached by a screw d² to the throat-plate 90 T. This deflector has inclined surfaces, as 20, at the inner sides of arms extending from an eye portion d¹, which has a certain amount of elasticity, so that the said arms under strain may be made to spring or somewhat separate 95 one from the other. By the employment of the deflector, should the points of the needles a b be deflected by reason of any hardness or inequality of the material so as not to correctly enter the slot 22 between the arms 100 of the deflector, then the needles, by striking just above their points against one or the

other of the inclined surfaces of the deflector, will be made to enter the said slot 22, and will stand there while the needle-bar is down side by side in proper line, so that the looper 5 *h*, as it is moved forward, will correctly enter the loops of needle-thread thrown out from both of the said needles.

The deflector referred to (see Fig. 1) is located sufficiently below the throat-plate as to 10 permit the looper *h* to pass between it and the throat-plate when entering the loops of needle-thread. The looper has two eyes 3 4, one near its heel and the other near its point, and the looper is grooved, as at 2, between the 15 said eyes at its inner side to receive the straight thread not a loop yet, the thread entering first the eye 3 and then out through the eye 4 to the stitch-forming point. The looper at its inner side is notched near its 20 heel to leave shoulders 12. The throat-plate at its right-hand side or its side nearest the heel of the looper is provided with a depression or shallow transverse groove *g*, Fig. 2, and a finger, as *n*, composed of a piece of wire 25 attached by a screw *n'*, the point of the said finger lying close to the right-hand side of the needle-hole (marked *n²*) in the throat-plate *T*, (see Fig. 2,) and extending partially over the 30 depressed portion to leave a space between the under side of the throat-plate and point of the finger.

Referring to the drawings, Fig. 1, it will be supposed that the looper provided with a thread is just about to enter the two loops thrown out from the farther sides of the two 35 needles *a* and *b*. After the point of the looper gets into the loops of needle-thread, the needles in their upward movement are withdrawn from the material, and the looper is moved 40 forward or to the left until both loops of needle-thread come into the notch at the heel of the looper and back of the shoulders 12. In this condition, while the needles are yet out of the material, the rocking frame *A²* is 45 rocked to move the looper bodily toward the operator, or in a direction opposite that of the feeding-movement given to the material, and then the looper is moved in the direction of its length back out of the loops of needle- 50 thread. As the looper is so withdrawn the shoulders 12, acting upon the loops of needle-thread, draw them aside to the right of the needle-hole until the looper has been retracted for about one-third its distance, when the 55 loops of needle-thread slip from the said shoulders and start forward toward the point of the looper, the looper also continuing to be retracted in the opposite direction. At this time the usefulness of the finger *n* be-

comes apparent, for the loops of needle-thread 60 which have slipped off from the shoulders 12 in their movement and while the needles *a* *b* are again descending pass up to and against the finger *n*, and the said loops are retained at the right-hand side of the finger and of the needle-hole *n²*, the loops lying 65 over the point of the finger between it and the under side of the throat-plate, while the needles *a* *b* descend at the rear side of the looper and between it and the thread carried 70 thereby. As soon as the points of the needles *a* *b* get into the loop of looper-thread, as described, the point of the looper in its backward movement comes out of the two loops of 75 needle-thread yet held by it and resting against the finger *n* at the right-hand side, letting the two loops be taken up into the material during the further descent of the needles *a* *b* and before the looper is again moved forward in the direction of its length into the 80 new loops of needle-thread formed below the material by the needles then down into substantially their lowest position.

I claim—

1. The combination, with two needles and 85 a looper and a throat-plate, of a yoke-like deflector located below the throat-plate and having spring-arms, the inner surfaces of said arms being beveled or inclined to place the needles side by side in order that the 90 loops of thread carried by them may be correctly entered by the looper and the needles enter the slot between the arms, substantially as described.

2. In a needle-bar, its two needles *a* *b*, the 95 looper having the shoulder 12, and the throat-plate, combined with the fixed finger *n*, connected to the under side of the throat-plate and located at the side of the needle-hole toward which the loops of needle-thread are 100 drawn by the reeding looper, and lying partially across the path in which the said looper reciprocates, the said finger retaining the said loops of needle-thread discharged from the shoulder 12 and preventing said loops while 105 yet engaged by the looper from slanting forward in the path of the descending needles, the further backward movement of the looper causing it to release the loops to enable the stitch to be repeated, substantially as described.

In testimony whereof I have signed my name to this specification in the presence of two subscribing witnesses.

LORENZ MUTHER.
